DOOR CLOSER

Bert A. Quinn, St. Paul, Minn., assignor to Ideal Brass Works, Inc., St. Paul, Minn., a corporation of Minnesota

Filed Mar. 8, 1963, Ser. No. 263,834

2 Claims. (Cl. 16—51)

My invention relates to fluid pressure-operated door closers of the type in which an actuating rod-equipped piston is mounted for extending and retracting movements within a fluid-containing cylinder, and has for its principal object a novel and highly effective means for sealing the end of the cylinder in which the actuating rod is slidably mounted for said extending and retracting movements.

In devices of the class immediately above described the cylinder is sealed to atmosphere only by sealing means such as a packing gland in the end wall of the cylinder in which the actuating rod is slidably mounted. Consequently, under conditions wherein the actuating rod becomes roughened or otherwise damaged by impact or the like, the efficiency of the closer is reduced in direct proportion to the damage which the roughened rod exerts upon the packing gland.

The primary object of my invention is the provision of novel sealing means for structures of the type immediately above described which does not have any direct contact with the reciprocating actuating rod, and the efficiency of which is not in any way affected or impaired by roughening of the actuating rod.

A further object of my invention is the provision of a device of the class described wherein the actuating rod may be produced at a minimum cost due to the fact that is not necessary to impart any polish thereto initially, and consequently it may be produced from stock material.

A further object of my invention is the provision of a device of the class immediately above described which is relatively inexpensive to produce, which is highly efficient in its operation, and which is extremely durable in use.

The above and still further objects of my invention will become apparent from the following detailed specification, appended claims and attached drawings.

Referring to the drawings wherein like characters indicate like parts throughout the several views:

FIG. 1 is a view in horizontal section through a door frame and cooperating door showing my door closer;

FIG. 2 is an enlarged view in axial section as seen from the line 2—2 of FIG. 1;

FIG. 3 is a view in side elevation of one form of the sealing member shown in FIG. 2 in its normal unstretched condition;

FIG. 4 is a fragmentary view in axial section similar to FIG. 3, portions thereof being broken away and illustrating different positions of some of the parts.

FIG. 5 is a view corresponding to FIG. 2 but showing a modified embodiment;

FIG. 6 is a view in perspective of the sealing means of FIG. 5; and

FIG. 7 is an enlarged view in axial section of the structure of FIG. 5, some parts being broken away and illustrating a different position of some of the parts.

Referring with greater particularity to the drawings, the letter A indicates in its entirety a conventional door frame, and B a conventional storm or screen door hingedly secured thereto.

The axially elongated metallic cylinder of my novel closure member is identified by the numeral 1, one end of which is provided with a closure means in the form of a plug 2, the axially outer end portion of which is

formed to provide conventional means 3 for pivotally connecting same to a bracket 4 mounted on the door B. The opposite end of the cylinder 1 is provided with partial closure means in the form of a plug 5 having a restricted axial opening 6 therein. Mounted for axial reciprocal movements within the cylinder 1 is a conventional piston 7 which, as shown, defines a radially outwardly opening groove 8 in which a sealing O-ring 9 is received for limited axial movements. Rigidly secured to the piston 7 and carried thereby is a radially reduced actuating rod 10 which is slidably received in the restricted axial opening 6 in the plug 5. As shown particularly by the enlarged view of FIG. 4, the fit between the actuating rod 10 and the restricted opening 6 is such as to permit the passage of air.

Shown as encompassing the actuating rod 10, with one end against the plug 5 and the other end against the piston 7, is a coil compression spring 11 which yieldingly biases the piston 7 in a direction to retract the actuating rod 10 substantially within the cylinder 1, as shown particularly by FIG. 2.

It will be noted that both the plug 5 and the piston 7 are formed to define opposed radially reduced annular bosses 12, 13 respectively. Extending between and telescoped over said bosses 12, 13 and sealed thereto by any suitable manner 12a, 13a is a flexible, collapsible, fluid-tight tubular member 14 which may be formed from any suitable plastic or rubber-like material. Under circumstances wherein the tube 14 is formed from elastic rubber-like material, its normal unstretched condition is indicated by FIG. 3. As shown in FIG. 2, when the elastic tube 14 of FIG. 3 is in operative position it is axially stretched by the coil compression spring 11 during actuating rod retracting movements. This arrangement has the advantage of creating a minimum of distortion and pleating of the side walls of the tube 14 during extending movements of the actuating rod 10, wherein the piston moves in the direction of plug 5, as shown in FIG. 4.

To insure a spacing of the walls of the tube 14 from the actuating rod 10 during extending and retracting movements, due primarily to pressure within the cylinder 1 (externally of the tube 14), caused by axial movement of the piston 7, I provide spacer means intermediate said tube and actuator rod 10 in the nature of a coil compression spring 15 which, as shown, is substantially the diameter of the reduced bosses 12, 13 and opposite ends of which abut against said bosses 12, 13.

All in conventional manner, the piston 7 is formed to provide a restricted passage 16 which communicates with the interior of the cylinder 1, intermediate the piston 7 and the plug 5, and the annular channel 8. During extending movements of the actuator rod 10, fluid within the cylinder 1 passes not only through the restricted opening 16 but around the entire periphery of the portion 7a and from thence through the enlarged opening 17 in the portion 7b, see particularly FIG. 4. On the other hand, when the actuating rod 10 is being retracted within the cylinder 1, the O-ring 9 moves axially into engagement with the portion 7a of the piston 7 and seals the passage of fluid thereabout, thereby limiting passage of fluid solely to the restricted aperture 16.

Referring again to FIG. 4 wherein the actuator rod 10 is shown as having working clearance with the plug 5, it should be obvious that even though the actuator rod 10 is roughened or otherwise damaged, no impairing effect will be had upon the operative efficiency of the sealing tube 14. This clearance likewise, of course, permits free passage of air into the space intermediate the tube 14 and the plunger rod 10 during movements of the piston 7 within the cylinder 1.

In the modified form of my invention shown in FIGS.

5 to 7 inclusive, the tube 18 is shown as having a reduced end portion 19, which is secured to the intermediate portion of the actuating rod 10 by any suitable manner, such as a clamping band 20, to effect a seal. At its opposite end the flexible tube 18 is formed to define a diametrically enlarged annular sealing flange 21, as shown particularly in FIGS. 5 and 7. This sealing flange 21 not only operatively engages the partial closure means 22, but also effectively engages the cylinder 1 and has sealing engagement therewith under yielding bias of the coil compression spring 11.

Preferably, and as shown, the partial closure means 22 is in the nature of a relatively thin annular washer over which the adjacent end 22a of cylinder 1 is rolled or crimped. The radially inner portion of the washer 15 22 is axially extruded as at 22b to form a loose bearing for the actuating rod 10.

In order to uniformly distribute the yielding bias of the coil spring 11, an annular compression washer 23 is interposed between the sealing flange 21 and the adjacent end of said coil spring 11. 20

With this structure, as shown particularly in FIG. 7, the reduced inner end portion 19 of the tube 18 is telescopically received within the tube 18 in direct proportion to the extending movement of the actuating rod 10 25 as the tube is backfolded upon itself. In this form of the invention, the tube 18 is not pleated during extending movements of the actuating rod and not stretched during retracting movements thereof. Furthermore, no spacing means need be interposed between the tube 18 30 and the shaft 10.

My invention has been thoroughly tested and found to be completely satisfactory from the accomplishment of the above objects, and while I have shown a preferred embodiment thereof, I wish it to be understood that same may be capable of modification without departure from the scope and spirit of the appended claims. 35

What I claim is:

1. In an extensible and retractable fluid pressure-operated closure device of the type adapted to be interposed between a door frame and a hingedly connected door, 40
  - (a) an axially elongated cylinder having closure means at one end,
  - (b) partial closure means at the other end of said cylinder and defining a restricted axial opening,
  - (c) a plunger member,

5
10

- (d) said plunger member including a piston mounted for axial sliding movements within said cylinder and having associated therewithin an actuating rod which is slidably received in said restricted opening,
- (e) yielding means in said cylinder biasing said piston in a direction to retract said actuating rod,
- (f) valve means operatively associated with said piston and restricting the passage therethrough of fluid within said cylinder during said retracting movements,
- (g) means sealing escape of fluid from said cylinder between said partial closure and said actuating rod during movements of said plunger,
- (h) said means including a longitudinally collapsible fluid impervious tube concentrically encompassing said actuating rod, one end of which has sealing engagement with said partial closure means and the opposite end of which has sealing engagement with said plunger in axially spaced relation to said partial closure means,
- (i) said yielding means comprising a coiled compression spring interposed between said cylinder and said tube, and
- (j) in further combination with collapsible and extensible spacer means interposed between said tube and said actuating rod and extending for substantially the full length of said tube.

2. The structure defined in claim 1 in which said partial closure means and said piston are formed to define opposed restricted annular bosses, the opposite ends of said tube being telescopically received over said bosses, and in which said spacer means is of substantially the same diameter as said restricted bosses and extends between said bosses. 35
